US0D1113875S

(12) **United States Design Patent** (10) **Patent No.:** **US D1,113,875 S**
(45) **Date of Patent:** **** Feb. 17, 2026**

- (54) **INTERFACE BOARD FOR RADIO FREQUENCY ANTENNA**
- (71) Applicant: **Battelle Memorial Institute**, Columbus, OH (US)
- (72) Inventors: **Raphael Joseph Welsh**, Powell, OH (US); **Thomas Lloyd Moffit**, San Diego, CA (US)
- (73) Assignee: **BATTELLE MEMORIAL INSTITUTE**, Columbus, OH (US)
- (**) Term: **15 Years**
- (21) Appl. No.: **29/898,401**
- (22) Filed: **Jul. 27, 2023**

Related U.S. Application Data

- (63) Continuation of application No. 18/139,620, filed on Apr. 26, 2023, now Pat. No. 11,936,415, which is a continuation-in-part of application No. 17/992,203, filed on Nov. 22, 2022, now Pat. No. 11,742,888, which is a continuation of application No. 17/141,796, filed on Jan. 5, 2021, now Pat. No. 11,552,670, which is a continuation of application No. 16/858,169, filed on Apr. 24, 2020, now Pat. No. 11,057,072.

(57) **CLAIM**

The ornamental design for an interface board for radio frequency antenna as shown and described.

DESCRIPTION

FIG. 1 is a first perspective view of a portion of the interface board taken from FIG. 2 and FIG. 3;

FIG. 2 is a second perspective view of the interface board; and,

FIG. 3 is a top view of the interface board.

(Continued)

The broken lines depict portions of the article and form no part of the claimed design. The dot-dash broken lines in FIG. 2 and FIG. 3 identify the portion that is represented in FIG. 1.
